SMOKE ELIMINATOR FOR BOILER FURNACES

Filed June 27, 1932

FIG. 1.

FIG. 3.

Inventor
James B. McNeil
by Arthur M. Moore, Atty.

UNITED STATES PATENT OFFICE

JAMES B. MCNEIL, OF PARK RIDGE, ILLINOIS

SMOKE ELIMINATOR FOR BOILER FURNACES

Application filed June 27, 1932. Serial No. 619,427.

This invention relates to improvements in smoke eliminators for boiler furnaces, and it consists of the matters hereinafter described and more particularly pointed out in the appended claims.

The primary object of the invention is to provide a simple and efficient device disposed in one of the walls of a furnace and opening at one end into the firebox thereof, to insure complete burning of all products of combustion, whereby a saving in fuel is attained and the discharge of smoke to the atmosphere with its attending objections, is avoided.

Another object of the invention is to provide a device of this kind embodying inner and outer conduits that open at one end into the firebox and communicate at their other end and employ in connection therewith a jet nozzle that discharges into one of said conduits so that products of combustion are drawn into the other conduit and there mingled with the steam issuing from said nozzle and atmospheric air to provide a mixture that is discharged back into the firebox and completes combustion therein.

Still another object of the invention is to provide a device of this kind which is applicable to locomotive boiler fireboxes as well as to stationary boiler fireboxes and which device may be made and sold at a low cost and may be installed in boiler fireboxes now in use in but a short time.

The above mentioned objects of the invention, as well as others, together with the many advantages thereof, will more fully appear as I proceed with my specification.

In the drawing:—

Fig. 1 is a transverse vertical detail sectional view through a part of the side water leg of a locomotive boiler in which one of my improved smoke eliminating devices is installed.

Fig. 2 is a horizontal sectional view through the same as taken on the line 2—2 of Fig. 1, the inner tube and its connecting fitting being shown in plan elevation.

Fig. 3 is a detail transverse vertical sectional view through a part of the same as taken on the line 3—3 of Fig. 1.

The invention is herein illustrated and

will be herein described, as embodied in a locomotive type of boiler but this is to be considered only as an example of one embodiment of the same, because as will be apparent the invention may also be embodied in other types of boilers, stationary or otherwise, when the peculiar characteristics of the invention make it of advantage to do so.

In general, the invention comprises means providing inner and outer concentric conduits, both of which open at one end into the firebox and which conduits communicate with each other near their other end. The other end of one conduit is closed off in a suitable manner while the corresponding end of the other conduit opens into a fitting which in turn opens at one end to atmosphere and has a steam jet nozzle therein that discharges into said other conduit. Under the action of the nozzle, an aspirating action is established in said fitting, which causes an inrush of atmospheric air thereinto that mixes with the steam and is discharged under pressure into said last mentioned conduit. As this mixture passes the openings whereby communication is established, between said conduits, a suction action is produced in said conduits. Products of combustion from the firebox are thus drawn into said first mentioned conduit to pass into the second one, where they mix with the air and steam to further raise the temperature thereof and be discharged at a relatively high temperature, pressure and velocity into the firebox. The combined mixture thus introduced into the firebox, insures complete combustion of the products of combustion in the firebox and thus eliminates the formation of smoke and its objectionable discharge out of the stack connected to the firebox.

Referring now in detail to that embodiment of the invention, illustrated in the accompanying drawing: 1 and 2 indicate respectively, the inner and outer spaced sheets of a locomotive firebox defining a side water leg 3. Extending between said sheets is a tube 4, suitably secured at its ends in said sheets in a pressure tight manner. In certain locomotive boilers, such tubes known as "combustion" tubes are present and when so

95

100

present, I make use of the same to apply other parts of my invention thereto. When such a tube is not already in place, a suitable opening is made in said sheets and such a tube is applied in position therein.

In the outer end of said tube, I secure an internally threaded ring 5 and preferably said ring is welded in place as indicated at 6. Within said tube 4, I provide a second tube 7 of smaller diameter and which is externally threaded at its outer end as best shown in Fig. 1 and in the diametrically opposite sides of said extremity of said end, I provide notches 7a. Such a tube which is of a length somewhat greater than that of the tube 4, is so threaded through the ring 5 as to be supported thereby and its outer end extends somewhat outwardly beyond said ring and its inner end extends a short distance beyond the inside of the inner sheet 1 of the firebox.

By means of the notches 7a, any suitable device may be engaged therein for imparting a turning movement to said tube from outside the firebox as when assembling said tube in position or when removing the same therefrom.

In the inner tube 7, near the ring 5 is provided a plurality of arcuately spaced, radially extending openings 8, each counterbored at its outer or inlet end as best shown in Fig. 3. On the outer end part of the inner tube 7 beyond the ring 5, is threaded one end of a T-fitting 9 and in the other end of said fitting is threaded a bushing 10, the right angled branch 11 of said fitting, opening to atmosphere and preferably facing downwardly to better prevent the entrance of foreign material thereinto.

In the bushing 10 is threaded a steam jet nozzle 12 so disposed that its inner end discharges axially into the outer end of the tube 7. The outer end of said jet nozzle receives the branch 13 of a second T-fitting 14, into opposite ends of which are threaded pipes 15 constituting headers leading from a source of steam supply and to a second and companion eliminator device. In locomotive boiler work there will be a number of devices, along the side of the firebox end of the boiler, and all devices on one side thereof, will be connected to said headers as is apparent.

The two tubes 4 and 7 coact to provide inner and outer conduits or chambers 16 and 17 respectively, both of which open at the inner end into the firebox, the outer end of the conduit 17 being closed by the ring 5, the outer end of the conduit 16 opening into the fitting 9 and both conduits communicating with each other by means of the openings 8.

The said tubes are so proportioned, that there is no possibility of cinders and the like of such size entering the conduit 17 as would clog up the holes 8.

In the operation of the device, with a steam jet being discharging from the nozzle

12, into the outer end of the tube 7, a subatmospheric condition is established in the fitting 9 so that air rushes into the same from below, through the branch 11 to mix therewith and enter the outer end of the tube 7. In the passage of this mixed air and steam through the tube under high velocity as induced by the jet nozzle, it passes the openings 8, and an aspirating action is produced in the outer conduit 17 so that the products of combustion are drawn from the firebox into said conduit. Said products of combustion then pass to the rear end of said conduit and through said holes 8 into the conduit 16 and mingle with the already mixed air and steam to produce a combined high temperature mixture of air, steam and products of combustion that is discharged back into the firebox from the inner end of the conduit 16 and which mixture promotes and completes combustion so as to insure an absence of a smoke discharge.

In the discharge of the mixture described from the inner end of the conduit 16 into the firebox, a vacuous annular zone is established about the inlet end of the outer conduit, thus creating a suction draft for the products of combustion in entering said chamber to completely fill the same. All cinders that are capable of entering the inlet end of this conduit are capable of passing out of the same through the holes or ports 8 to enter the inner conduit for a discharge back into the firebox so that the device at all times is self-cleaning.

Again, as the conduit 17 is completely filled with products of combustion at high temperature, the tube 4 acts to heat the water surrounding the same and said high temperature is also transmitted to the inner tube so that there is no cooling effect by the combined mixture to be discharged into the firebox, and upon the products of combustion therein, and there is no cooling effect imposed upon the water in the side water leg surrounding the tube 4.

By the construction described, with respect to the jet nozzle 12, the same may be adjusted longitudinally to bring its discharge tip into that position providing the best operation of the device for its intended purpose.

While in describing the invention, I have referred in detail to the form, arrangement and construction of the various parts thereof, the same is to be considered merely illustrative so that I do not wish to be limited thereto except as may be specifically set forth in the appended claims.

I claim as my invention:—

1. In combination with the wall of a firebox and means therein providing inner and outer conduits, both opening at their inner ends into the firebox and communicating with each other near their outer ends and one of said conduits being closed at said outer

end, means providing an air inlet communicating only with the outer end of said other conduit and a jet nozzle associated with said last mentioned means and adapted to discharge into the outer end of said last mentioned conduit.

2. In combination with the wall of a firebox and means providing inner and outer conduits therein both opening at their inner ends into the firebox and communicating with each other near their outer ends and the outer conduit being closed at its outer end, means providing an air inlet communicating only with the outer end of the inner conduit and a jet nozzle extending into said last means and adapted to discharge into the outer end of said inner conduit.

3. In combination with the wall of a firebox and means providing a conduit therein which opens at its inner end into the firebox, means closing the outer end of said conduit, a tube arranged in said conduit and opening at one end into said firebox and supported in position near its outer end by said closing means, said tube having openings therein near said closing means and establishing communication between said conduit and tube, means providing an air inlet communicating only with the outer end of said tube, and a jet nozzle arranged to discharge axially into the outer end of said tube.

4. In combination with the wall of a firebox and means providing a conduit therein which opens at its inner end into the firebox, means closing the outer end of said conduit, a tube arranged in said conduit and opening at one end into said firebox and supported in position near its outer end by said closing means, said tube having openings therein near said closing means and establishing communication between said conduit and tube, means providing an air inlet communicating only with the outer end of said tube beyond said closing means and a jet nozzle supported in said air inlet providing means and adapted to discharge into the outer end of said tube.

5. In combination with the wall of a firebox and means providing a conduit therein which opens at its inner end into the firebox, means closing the outer end of said conduit, a tube arranged in said conduit and opening at one end into the firebox and supported in position near its outer end by said closing means, said tube having openings therein near said closing means and establishing communication between said conduit and tube, a member secured to the outer end of said tube and having an air inlet arranged at an angle to the axis of said tube and communicating only with said outer end of said tube, and a jet nozzle supported in said member and arranged to discharge axially into the outer end of said tube.

6. In combination with a firebox a tube

arranged to discharge at one end into the firebox, means associated with the other end of said tube for discharging air and steam thereinto, means providing a conduit surrounding said tube and having its inlet end opening into the firebox and having its other end in communication with said tube near said first mentioned means and out of communication with said air and steam discharge means, said tube operating when air and steam are discharged into its said other end to create an aspirating action on that end of the conduit in communication with said tube and draw into said tube products of combustion for mixing with the air and steam and raising the temperature of said air and steam prior to the discharge into the firebox.

7. In combination with the wall of a firebox and means providing a conduit therein which opens at its inner end into the firebox, means closing the outer end of said conduit, a tube arranged in said conduit and opening at one end into the firebox and supported in position near its outer end by said closing means, said tube having openings therein near said closing means and establishing communication between said conduit and tube, said openings in said tube being of a larger diameter at that end opening into said conduit, means providing an air inlet conduit communicating only with the outer end of said tube and a jet nozzle arranged to discharge axially into the outer end of the tube.

8. In combination with the wall of a firebox and means providing a conduit therein which opens at its inner end into the firebox, means closing the outer end of said conduit, a tube arranged in said conduit and opening at one end into the firebox and supported in position near its outer end by said closing means, said tube having openings therein near said closing means and establishing communication between said conduit and tube, said openings having a diameter approximating the dimension of the spacing between said conduit providing means and tube, means providing an air inlet communicating only with the outer end of said tube, and a jet nozzle arranged to discharge axially into the outer end of said tube.

9. In combination with the inner and outer side sheets of a locomotive boiler firebox, a tube fixed at its end in said sheets and opening at its inner end into the firebox, an annular member disposed in the outer end of said tube, a second and smaller tube arranged in the first mentioned tube for discharging at one end into said firebox, said second and smaller tube being supported in position by said annular member and having openings near said member affording communication between said tubes, means providing an air inlet communicating only with the outer end of said smaller tube, and

means providing a jet nozzle for discharging axially into the outer end of said smaller tube.

10. In combination with the inner and outer side sheets of a locomotive boiler firebox, a tube fixed at its end in said sheets and opening at its inner end into the firebox, an annular member disposed in the outer end of said tube, a second and smaller tube arranged in the first mentioned tube for discharging at one end into said firebox, said second and smaller tube being supported in position by said annular member and having openings near said member affording communication between said tubes, means providing an air inlet fitting on and supported by the outer end of said smaller tube and communicating only with the outer end of the same and a jet nozzle supported in said last mentioned means so as to discharge axially into the outer end of said smaller tube.

11. In a device of the kind described, the combination of a wall associated with a firebox, means providing an inner conduit and a surrounding outer conduit, both of said conduits opening at their inner ends into the firebox and both being unbroken throughout

their length except for communicating openings therebetween at one end, means providing an air inlet to one only of said conduits at its outer end and a jet nozzle associated with said end of the last mentioned conduit and discharging thereinto as and for the purpose specified.

12. In a device of the kind described, the combination of a wall associated with a firebox, a tube arranged therein and closed at its outer end and opening at its inner end into the firebox to provide for the inlet of products of combustion thereinto, a second tube in the first tube and communicating near its outer end with the outer end of said first tube and also opening into the firebox at its other end for the discharge of a mixture blast thereinto, means providing an air inlet for the outer end of said second tube only and a jet nozzle arranged in said last mentioned means so as to discharge a mixture of air and steam only into the outer end of said second tube.

In testimony whereof, I have hereunto set my hand, this 24th day of June, 1932.

JAMES B. McNEIL.
